United States Patent Office

Des. 185,315
Patented May 26, 1959

185,315

WIENER SKINNER

Forrest J. Robinson, West Union, Iowa

Application July 16, 1958, Serial No. 51,808

Term of patent 7 years

(Cl. D55—1)

Des. 185,315

PAGE 2

FIG. 3

Fig. 1 is a perspective front view of a wiener skinner showing my new design;

Fig. 2 is a perspective rear view thereof; and
Fig. 3 is a front elevational view.

I claim:

The ornamental design for a wiener skinner, as shown.
